No. 678,674.

Patented July 16, 1901.

O. MICHAEL.

CRUCIBLE FURNACE.

(Application filed June 14, 1901.)

(No Model.)

UNITED STATES PATENT OFFICE.

OTTO MICHAEL, OF FREIBURG, GERMANY.

CRUCIBLE-FURNACE.

SPECIFICATION forming part of Letters Patent No. 678,674, dated July 16, 1901.

Application filed June 14, 1901. Serial No. 64,502. (No model.)

To all whom it may concern:

Be it known that I, OTTO MICHAEL, foundry-
foreman, a subject of the Grand Duke of Baden,
residing at Guntramstrasse 36, Frei-
5 burg, in the Grand Duchy of Baden and Em-
pire of Germany, have invented certain new
and useful Improvements in Crucible-Fur-
naces, of which the following is a full, clear,
and exact description.

10 In the whole industry of metal founding,
and especially in the construction of crucible-
furnaces, a great many novelties have been
introduced from time to time. They have
been mostly of such an unpractical nature,
15 however, that they have had to give way to
the old processes—the crucible, cupola, and re-
verberatory furnaces—notwithstanding that
it has always been clear to those engaged
in such industry that the old crucible-fur-
20 naces, which do not change the chemical com-
position of the smelting charge to any ap-
preciable degree, work very unprofitably by
reason of their great consumption of fuel.
It has been proposed, for instance, to place
25 several crucibles in one furnace or to set
crucibles in flues a certain distance above the
floor of the furnace for heating the mass
where the heat of the waste gases may be
utilized; but even in these methods a large
30 and continuous consumption of fuel is im-
perative, otherwise the heat will be insuffi-
cient.

It is well if a really workable smelting
35 plant is to be set up to start from the basis
of utilizing the heat of waste gases before it
escapes farther into the flues leading to the
stack without the heated crucibles being
placed in the oven for a second heating period.
This is the purpose and subject-matter of the
40 present invention, according to which the
crucibles to be heated are placed within niches
provided in the mouths of the flues in the fur-
nace on the same level as the usual grating
or floor, and the material contained in them
45 becomes melted even at the first period of
warming, no matter whether it is not readily
fusible or otherwise, so that the contents of
the crucible may be poured out immediately
after the first melting period, together with
50 those crucibles that have passed through their
second melting period.

Upon the accompanying sheet of drawings

is shown the means for carrying out my in-
vention.

Figure 1 is a vertical section through the 55
line A B of Fig. 2, and Fig. 2 a horizontal sec-
tion on line C D of Fig. 1.

The horizontal section of the crucible-cham-
ber *a* of the oven is shown quadrilateral in
Fig. 2; but it may be of any other shape. In 60
the middle of each of the four walls is built
a niche of curved form *b*, four in all. These
niches *b* are of convenient height, so that cru-
cibles or melting-pots *c*, provided with covers
65 *d*, can stand therein upon suitable bases *e*,
the crucibles being introduced through the
crucible-chamber *a* into the niches *b* at the
mouths of flues *f*, which form a continua-
tion of the niches *b*, and removed by the same
way. 70

The floor of the crucible-chamber *a* is made
of a grating *g*, composed, preferably, of rec-
tangular section-bars. Beneath and across
the bars of the grating are two double T-
girders *h* or a frame of similar section, which 75
convey to the brick wall *i* of the furnace the
weight of the filled crucibles *p* standing on
the grating *g*. Underneath the grating *g* is
an ash-pit *k*, easily reachable and readily
cleaned. Opening into the outer walls of the 80
niches *b* somewhat, as shown in Fig. 1, are
channels *l* at a suitable height above the cru-
cibles *c*, leading from the flues into the stack.
It is advantageous to let the individual branch
channels *l* lead into a common flue *n* built 85
in the wall *i* of the furnace around the cru-
cible-chamber *a* before finally leading into
the main flue, by which arrangement the
draft from the individual channels *l* can be
equalized. For the purpose just mentioned 90
it is advisable to make the main flue termi-
nate at different points—for example, at two
points in the flue *n*, as shown by Fig. 2.

The surfaces of the furnace that come in
direct contact with the fire are preferably 95
covered with dolomite, ganister, or like suit-
able material.

The above-mentioned operation takes place
in the crucible-furnace according to the pres-
ent invention as follows: Supposing the four 100
crucibles *p* standing in the middle of the cru-
cible-chamber *a* to be taken out (together
with the molten material contained therein)
and the lid *q* (made of stone, &c.) removed

and the interior of the shaft thus exposed, the crucibles *c*, which were heated during the last smelting, so as to melt the greater part of the contents, are then taken out one by one, while other crucibles *c*, containing fresh unmelted material, are put in place thereof into the niches *b*. The crucibles *c*, which have just been removed from the niches *b* after their first heating, are now assembled 10 in the places previously occupied by the crucibles *p*, as shown in the drawings, in the center of the crucible-chamber *a*, where they remain for the second heating. The space in the crucible-chamber *a* between the separate 15 pots or crucibles *p* is filled up with coke, which done the second heating begins.

What I claim, and desire to secure by Letters Patent, is—

1. A crucible-furnace comprising a crucible-chamber, niches in the walls of the chamber for the reception of crucibles to be pre-heated, channels leading from the outer walls 20

of the niches, and means for heating the furnace.

2. A crucible-furnace comprising a crucible-chamber, niches in the walls of the chamber for the reception of crucibles to be pre-heated, channels leading from the outer walls of the niches, a main flue surrounding the chamber and common to all the channels, 25 and means for heating the furnace.

3. A crucible-furnace comprising a crucible-chamber, means for heating the furnace having a grate, niches in the walls of the chamber for the reception of crucibles to be 30 preheated, having floors on the same level as the grate and channels leading from the outer walls of the niches.

In witness whereof I subscribe my signature in presence of two witnesses.

OTTO MICHAEL.
